(57) **CLAIM**

The ornamental design for a reaction vessel for amplifying nucleic acid, as shown and described.

DESCRIPTION

FIG. 1 is a perspective view of the reaction vessel for amplifying nucleic acid showing my new design;
FIG. 2 is another perspective view thereof;
FIG. 3 is a front elevational view thereof, the right side, left side, and rear elevational views thereof being the same;
FIG. 4 is a top plan view thereof;
FIG. 5 is a bottom plan view thereof; and,
FIG. 6 is a sectional view thereof.
